ATTACHMENT FOR HOLLYWOOD BEDS

Arthur L. Logan, Floral Park, N. Y.

Application June 9, 1950, Serial No. 167,229

6 Claims. (Cl. 5—318)

1

This invention relates to an attachment for "Hollywood" beds.

A "Hollywood" bed is characterized by the absence of head and footboard, being supported by legs which are secured directly to the frame of the springs. The desirability of a "Hollywood" bed stems largely from its attractive appearance due to the absence of head and footboard, which permits the bed to be completely covered by the spread which normally overhangs the sides and ends of the bed.

One of the disadvantages is that at night, due to lack of a footboard, there is no proper place to stow the spread when it is turned down. It must be taken off, folded and put away, or it may be turned down and left in partially spread state across the lower part of the bed. This imposes undue weight upon the feet of the sleeper, so that the spread generally becomes kicked off on the floor. Likewise, there is no place to keep an extra blanket in readiness. If laid on the foot of the bed it is generally pushed off, so that when needed the sleeper has to get out of bed in order to retrieve it.

The object of the present invention is to provide a rack at the foot of a "Hollywood" bed which can be readily attached thereto, being adjustable from a collapsed position beneath the bed, by day, when it may be completely concealed beneath the overhanging bedspread, to an erect position by night, in which it becomes a footboard, affording convenient support for the turned down bedspread or for the extra blanket, as well as affording means confronting the lower end of the mattress, when in erect position, between which means and the mattress the bed covers remain tucked so that they will not be pulled away from the foot of the bed by a restless sleeper.

Other objects of the invention will appear as the following description of a preferred and practical embodiment thereof proceeds.

In the drawing which accompanies and forms a part of the following specification and throughout the figures of which the same reference characters have been used to denote identical parts:

Figure 1 is a side elevation of the foot portion of a "Hollywood" bed, illustrating the rack attachment in erect position;

Figure 2 is a view in elevation of the foot end, the rack being erect;

Figure 3 is a vertical section taken along the line 3—3 of Figure 2;

Figure 4 is a perspective view of one of the rack brackets, a part being broken away;

2

Figure 5 is a section taken along the line 5—5 of Figure 3;

Figure 6 is a section taken along the line 6—6 of Figure 1;

Figure 7 is a side elevation, partly in section, of the foot portion of the bed viewed from the inside, the rack being in collapsed position.

Referring now in detail to the several figures, the numeral 1 represents the springs of a "Hollywood" bed, having the rigid peripheral frame 2, and upon which is the mattress 3. At the head and foot are the legs 4, only the legs at the foot being shown. These are rigidly secured to the frame of the springs in the conventional manner.

10 The attachment of the present invention comprises three cooperating units, the brackets 5, one associated with each of the legs 4 at the foot, and the movable rack 6, which is operatively associated with the brackets. Each bracket comprises a side plate 7 perforated for bolts or screws by means of which the bracket is attached to the leg, a face plate 8 at right angles to the side plate 7 and welded or otherwise made unitary therewith, and an upwardly inclined channel member 9 welded to the rear of the face plate.

15 Figures 1 and 7 best show the bracket 5 secured to the leg with the channel member 9 extending forwardly and upwardly to a point at which it closely approaches the frame 2 of the bed springs. At this point the channel member 9 has attached thereto, by welding or in any other manner, a clip 10, the outer side of which extends in the form of an inverted hook 11, so shaped as to hook over the frame 2 and hold the channel member 9 in position.

20 The face plate 8 has an offset tongue 12 which is offset away from the surface of the face plate and lies parallel to the face plate. The width of the tongue 12 is less than the width of the hole 13, from which it is offset, so that the projection of the tongue upon the plane of the hole is not congruent but leaves a slot 14 at one side of the free edge of the tongue. The tongue is also cut off at the top so as to leave a relatively wide slot 15 between the tongue and hole. One of these brackets is secured to the inside of the leg 4 at each side of the bed.

25 Figure 2 shows that the rack 6 is composed of two vertical side members 16, a top bar 17 secured thereto, and diagonal struts 18 extending between the vertical members 16 and the top bar 17.

The vertical side members 16 are of right angular cross-section, having a top flange 19 and a side flange 20. The top flange plays in the slot 15 and the side flange in the slot 14 of the

bracket 5. It will be noted in Figure 7 that the member 16 at its free end is slotted along the apex of the dihedral between the two flanges, and that the top flange 19 is offset from the side flange to form a lug 22 parallel to the plane of said top flange defining a slot 21 between said lug and the upper edge of said side flange. The slot 15 is made relatively wide so as to enable the member 16 of the rack to be inserted into the brackets through the slots 15, including the relatively wide ends of the members 16 created by the offset lug 22.

The inner end of the members 16 are within the channel members 9 and slide along the floors of said channel members as the rack is raised towards a vertical plane or lowered into its fully collapsed position shown in Figure 7.

As the rack 6 approaches the vertical, the top flange comes out through the slot 15, until finally when the rack is in vertical position the entire top flange with the exception of the lug 22, lies outside of the face plate 8, between said face plate and the tongue 12. When the rack reaches this position it is pushed in a downward direction, which causes the lug 22 to come down behind the face plate 8, the lower part of said face plate designated as 23 being within the slot 21. Through the interdigititation of the slotted ends of the side members 16 with the lower parts 23 of the face plates, the rack is positively held rigidly in an upright or vertical position with its side members 16 and struts 18 contacting the down folded end of the bed spread at spaced points, as clearly shown in Figures 1 and 2. When it is desired to collapse the rack, it is first pulled in an upward direction in order to disengage the slotted member 16 from the face plates, whereupon, it may be tilted and pushed back through the slots 14 and 15, the inner end sliding upon the bottom of the channel member 9 in the manner already described.

When in fully collapsed position, only the top bar 17 projects, as shown in Figure 7, this being readily and completely concealed by the overhanging bedspread.

Figure 5 shows that the diagonal struts 18 have an offset portion 24, which enables the struts 18 to clear the tongue 12 of the bracket 5.

It will be apparent from the above description that this rack attachment gives all the advantages of a footboard without the unsightly lines of one, in the daytime, to spoil the smoothness and compactness which characterizes the "Hollywood" bed. The facility of operation, as well as the ease of attachment, and the possibility of making the attachment of plastic of different colors if desired, all contribute to making this attachment a useful and desirable article of manufacture. It need not necessarily be regarded as an attachment, but may be incorporated in "Hollywood" beds at the time of their manufacture.

While I have in the above description disclosed what I believe to be a preferred and practical embodiment of the invention, it will be understood by those skilled in the art that the specific details of construction and arrangement of parts, as shown, are by way of example and not to be construed as limiting the scope of the invention.

What I claim as my invention is:

1. An attachment for a "Hollywood" bed comprising a pair of similar brackets having means by which they may be respectively secured to the opposite legs at the foot of the bed, and a rack including side members and a top member connected therebetween, said side members being

tiltably and slidably mounted in said brackets with a range of movement from an erect position at the foot of the bed predominantly on the outside of said brackets to a recumbent position predominantly on the inside of said brackets and beneath the bed.

2. An attachment for a "Hollywood" bed comprising a pair of brackets, each comprising a face plate having a tongue offset from the plane of said face plate and defining with the edges of the opening from which it was struck, communicating slots through said face plate at the top and free side of said tongue, said brackets each including a perforated side plate to be secured to a leg of the bed adjacent the foot, each bracket having a channel member secured to said face plate below said slot, on the side opposite said tongue, having means adjacent the end remote from said face plate for supporting it upon a longitudinal member of the bed, a rack comprising side members of right angular cross-section having top and side flanges, a transverse top bar connected between said side members, the latter members being slidably and tiltably mounted in said brackets with their flanges in the respective slots and with their lower ends within said channel members, said rack being movable from a recumbent position in which its side members are predominantly inside of said face plate and beneath the bed to an erect position at the foot of the bed in which it is predominantly inside of said face plates with a flange of each side member between the corresponding face plate and its tongue, the lower ends of said side members being slotted between their top and side flanges, to permit said flanges to embrace said face plates below said tongues for maintaining said rack erect.

3. An attachment for a "Hollywood" bed comprising brackets attachable to the opposite legs adjacent the foot of the bed, said brackets each having a guide member adapted to extend longitudinally of the bed and having means for supporting it upon a longitudinal member of the bed, and a rack including a pair of parallel side members and a connecting transverse member, said side members being tiltably and slidably mounted in said brackets with their lower ends engaging said guide means, said rack being movable from a recumbent position predominantly inside of said brackets and beneath the bed, to an erect position at the foot of the bed predominantly outside of said brackets.

4. An attachment for a "Hollywood" bed as claimed in claim 3, said side members being provided with means engageable with said brackets when said side members are erect for maintaining them erect.

5. An attachment for a "Hollywood" bed comprising brackets attachable to the opposite legs adjacent the foot of the bed, said brackets each including a face plate and a tongue offset from the plane of said face plate, each bracket having a guide member adapted to extend longitudinally of the bed and having means for supporting it upon a longitudinal member of the bed, and a rack including a pair of parallel side members and a connecting transverse member, said side members being tiltably and slidably movable through apertures in said face plates with their lower ends engaging said guide members, through a range of movement from a recumbent position in which they are predominantly beneath the bed and inside of said brackets to an erect position at

the foot of the bed between said face plates and tongues.

6. An attachment for a "Hollywood" bed comprising a pair of similar brackets having means by which they may be secured at transversely spaced points to the bed adjacent the foot, and a rack including side members and a top member connected therebetween, said side members being tiltably and slidably mounted in said brackets with a range of movement from an erect position at the foot of the bed predominantly outside of said brackets to a recumbent position

predominantly beneath the bed inside of said brackets.
